UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

SPRING-HINGE.

SPECIFICATION forming part of Letters Patent No. 747,275, dated December 15, 1903.

Application filed October 1, 1903. Serial No. 175,309. (No model.)

To all whom it may concern:

Be it known that I, HENRY TSCHERNING, a citizen of the United States of America, residing at Freeport, in the county of Stephenson and State of Illinois, have invented certain new and useful Improvements in Spring-Hinges, of which the following is a specification.

My invention relates to certain improvements in spring-hinges, having to do particularly with the form and arrangement of a spring therein, by reason of which said spring is made easy of application to and removable from the hinge and is held therein against movement in all undesirable directions by its peculiar form and combination with the holding means employed in connection therewith.

The invention is illustrated in the drawings by means of four figures, of which—

Figure 1 is a face view of my improved hinge in its preferred form. Fig. 2 is an elevation. Fig. 3 is a horizontal section looking downward upon a plane 3 3 of Fig. 1, and Fig. 4 is a similar section looking downward upon a plane 4 4 of Fig. 1.

Referring to the drawings, a hinge A is made up of two leaves a a', pivoted together by means of rivets B C passing through the ears a² a'² upon the leaf a and the ears a³ a'³ upon the leaf a'. A vertical cylindrical socket a⁴ is provided at the left-hand side of the left-hand leaf, and a wire spring D is secured in said socket by means of a vertical portion d, turns to the right below said socket to form a spring-coil d', and extends upward from the left-hand side of said coil to the upper portion of the hinge, where it is connected by means of a small link E with a perforated tongue

a⁵ on the leaf a. The tension of the spring is such as to pull upon the link E and to press the coil d' against the leaf a'. This holds the spring securely in place, and it will be readily seen that the insertion of the spring in its place in the hinge may be effected very easily and readily by thrusting the part d of the wire into the socket a⁴ and then crowding the upper end of the spring to the right sufficiently to hook it into the link E. After being once put in this position the tension of the spring itself holds it against movement away from the leaf a', and the link E and the ear a⁵, at the lower end of the leaf a', both oppose longitudinal movement of the spring in a direction opposite to that in which it was placed in the hinge.

I claim as new and desire to secure by Letters Patent—

In a spring-hinge, the combination with the pivoted leaves, one of which has a longitudinal socket at its outer edge and the other of which has an eye at its inner edge, of a spring having an arm connected with said eye, a coil on the side of said arm toward the other leaf and a second arm crossing the first and provided beyond the same with a portion bent to enter said socket, whereby the tension of the spring holds the coil against the leaf to which it is secured.

In witness whereof I have signed the above application for Letters Patent, at Freeport, in the county of Stephenson and State of Illinois, this 25th day of September, A. D. 1903.

HENRY TSCHERNING.
